UNITED STATES PATENT OFFICE.

ARTHUR G. PERKINS, OF COVENTRY, ENGLAND.

LADDER.

SPECIFICATION forming part of Letters Patent No. 575,759, dated January 26, 1897.

Application filed April 16, 1896. Serial No. 587,883. (No model.)

To all whom it may concern:

Be it known that I, ARTHUR GEORGE PERKINS, a subject of the Queen of Great Britain, and a resident of Coventry, in the county of 5 Warwick, England, have invented certain new and useful Improvements in Ladders, of which the following is a full, clear, and exact specification thereof.

This invention relates to improvements in 10 or relating to ladders, and the same is carried out as follows, reference being had to the annexed drawings, in which—

Figure 1 is an elevation of my invention in 15 position; Fig. 2, a section through line $x y$ in Fig. 1. Fig. 3 is a perspective view of my invention when used as a step-ladder.

a is the bottom half of my ladder, having 20 its uprights or sides of the grooved or tubular shape shown in Fig. 2. b is the top half of the ladder, which slides 25 into the grooved or tubular sides of the bottom half a , each part a and b having holes c and d , respectively, corresponding with one another, so that set-screws $e e$ may be passed 30 through same for the purpose of adjusting the height of the ladder.

When it is desired to employ the ladder as a pair of steps or step-ladder, the part b is withdrawn from the part a , and the ends $f f$ 35 of same, which are pointed, as shown, are

passed through the holes $g g$ in the top of part a , the hinged clips $h h$ engaging with the pointed ends, as shown in Fig. 3, for the purpose of retaining the parts a and b in their relative position.

Having thus described my invention, what I claim, and desire to secure by Letters Patent, is—

In convertible or adjustable ladders of the class herein described, a ladder formed in two 40 sections one section having side rails which slide in grooves in the side rails of the other section or part, bolts or pins passing through suitable apertures in said side rails for the purpose of maintaining the sections in any 45 desired position, there being apertures at or about the end of one section, in which the ends or projections upon the other section engage when for use as a step-ladder, a clip for securing same in position all in combination 50 substantially as described and illustrated herein.

In testimony that I claim the foregoing I have hereunto set my hand this 9th day of January, 1896.

ARTHUR G. PERKINS.
